UNITED STATES PATENT OFFICE.

WILLIAM RHODES, OF NEW YORK, N. Y.

RAILROAD-SWITCH.

SPECIFICATION forming part of Letters Patent No. 236,260, dated January 4, 1881.

Application filed September 27, 1880. (Model.)

To all whom it may concern:

Be it known that I, WILLIAM RHODES, a citizen of the United States, residing at New York, in the county of New York and State 5 of New York, have invented new and useful Improvements in a Railroad-Switch; and I do hereby declare that the following is a full, clear, and exact description of the invention, which will enable others skilled in the art to which 10 it appertains to make and use the same.

In the accompanying drawings, in which similar letters of reference indicate like parts, Figure 1 is a plan view of a section of railroad embodying my invention, showing the switch set for the siding and the signal in corresponding position. Fig. 2 is a view, in elevation, of a like section of railroad, showing the switch in like position. Fig. 3 is a front view of the signal. Fig. 4 is a plan view of the 15 shifting brace; Fig. 5, a sectional view of the shifting brace, and Fig. 6 a side view of the detecting-bar.

The invention consists in so arranging a connected series of rods, bell-crank, and springs 20 as to operate the switch, the lock, the signal, and the detecting-bar simultaneously by the action of a single lever located at the station or other desirable point.

In the drawings, A is a lever. B is a rod, 25 that may connect with the bell-crank D or the bell-crank D'. If B connects with the bell-crank D the rod B' will connect the bell-crank D to the bell-crank D'. The rod b' connects the bell-crank D' to the swinging end of the 30 shifting brace E. The reciprocating braces E and E' are attached to the frame P at the common center I.

The spiral tension spring G has one end attached to the swinging end of the brace E, 35 and the other end of the spring G is attached to the swinging end of the swinging brace E', so arranged that the movement of the lever A, swinging said end of brace E to one side or the other of center I, causes the free end of 40 the brace E', pivoted upon the said center, to swing similarly to one side or the other of said center by reason of the drawing tension of the spring G. The said movement of the free end of the brace E opens and closes 45 the switch K K by the longitudinal movement of the connecting link or rod C. The longi-

tudinal movement of the connecting-rod C is communicated to the connecting-rod C', which actuates the bell-crank k', connected to the signal k by the rod C.

55

Attached to the reciprocating end of E' is the plate F, mortised at f f to receive the sliding bolt y. This bolt is actuated by the rod N, one end of which is held in connection with a projection upon the free end of brace E by a 60 nut and compression-spring, a, while the other end of the rod is secured to the bolt. As during the vibration of braces E and E' the distance between their ends lengthened midway of the vibration and shortened at the extremities of the vibration, it will be seen that during the first half of the vibration of E the bolt Y will be withdrawn from the mortise f, and as the brace E moves on in the last half of the vibration the brace E' will be promptly 65 70 vibrated by the drawing tension of the spring G before the final movement of E shall have again thrust the bolt Y into the mortise f.

When the switch-lock is held back by a nut applied at R the switch K K will operate as 75 a trailing-switch, and trains may be run onto the main track through it from either the main or side tracks. Attached to and actuated by a bell-crank, D, is the connecting-rod b, moving simultaneously with the switch-rails K K, 80 and operating the lever S, one end of which lever being inserted in the notch h of the detecting-bar H, slides it longitudinally over the supports X X. The notches h' in the under side of H allow it to sink below the level of 85 the rail at the extreme limit of its longitudinal movement, out of reach of the flanges of the passing car-wheel, and the separating elevation T prevents H from moving longitudinally over the supports X X when H is held 90 down by the flange of the car-wheel above it, and thus blocks the movement of the switch-rails K K.

What I claim is—

1. The shifting braces E E', and the spiral 95 spring G, in combination with connecting-rods and one or more bell-crank, and the actuating-lever A, substantially as described.
2. The reciprocating braces E and E', and the spiral spring G, in combination with the 100 connecting-rod C, the switch-rails K K, arranged and operating in the manner specified.

3. The reciprocating braces E E', and the spiral spring G, in combination with the crank, connecting-rods, and signal k, for the uses as described.
4. The combination of the actuating-lever A, with the rods, cranks, braces, and springs, with the locking-bolt Y, constructed and operating as shown and described.
5. The detecting-bar H, having the notches h and h', in combination with the supports X and X, and a railroad-switch operating in the manner and for the purposes described and shown.

WILLIAM RHODES.
